UNITED STATES PATENT OFFICE.

EDWIN JAMES GARFIELD MACINTYRE, OF CLARENCE, ONTARIO, CANADA, ASSIGNOR
OF ONE-HALF TO BERNARD JOSEPH NOLAN, OF OTTAWA, ONTARIO, CANADA.

OIL BURNER.

1,409,145.

Specification of Letters Patent.

Patented Mar. 7, 1922.

Application filed October 18, 1917, Serial No. 197,295. Renewed September 3, 1921. Serial No. 498,589.

(GRANTED UNDER THE PROVISIONS OF THE ACT OF MARCH 3, 1921, 41 STAT. L., 1313.)

To all whom it may concern:

Be it known that I, EDWIN JAMES GARFIELD MACINTYRE, a subject of the King of Great Britain, and resident of Clarence, in the Province of Ontario, Dominion of Canada, have invented certain new and useful Improvements in Oil Burners, and do hereby declare that the following is a full, clear, and exact description of the invention, such 10 as will enable those skilled in the art to which it appertains to make and use the same.

This invention relates to improvements in oil burners adapted for use with crude oil and other heavy hydrocarbons and the objects of the invention are to facilitate atomizing the oil and mixing the same with the requisite proportion of steam to form a combustible mixture, to increase the efficiency of the burner and permit of the several parts 20 being readily assembled and disassembled, to so control the flow of the oil and steam that the size of the flame may be adjusted to suit the conditions under which the burner is working and generally to adapt 25 the several parts to better perform the functions required of them.

With the above and other objects in view the invention consists essentially of the improved construction particularly described 30 and set forth in the following specification and accompanying drawings forming part of the same.

In the drawings;

Figure 1 is a sectional elevation of a boiler 35 setting embodying the present invention.

Figure 2 is a longitudinal section of the improved burner.

Figure 3 is an enlarged longitudinal section of the ejector.

Figure 4 is a transverse section on the 40 line 2—2 of Figure 2.

Like characters of reference refer to like parts in the several figures.

Referring to the drawings, A represents a 45 boiler of any usual construction below which the fire box 10 is located, provided with a doorway 11 having an orifice therethrough through which the improved oil burner B extends.

This oil burner B consists of an inner tube 12 having a plurality of curvilinear slots 13 therein staggered relatively to each other and this tube is provided at one end with a

cap 9 forming a dead end while the other end of the tube is threaded as shown at 14. 55

A reducing union 15 makes threaded engagement with the end 14 and is also connected to one end of the outer pipe 16 the other end of which is threaded to a cap or cover 17 having a plurality of curvilinear 60 slots 18 therethrough.

The outer pipe 16 is spaced from the inner tube 12 forming an annular passageway or chamber 19 to which superheated steam is delivered from the pipe 20 passing through 65 the union 15.

The tube 12 is connected to the conduit or pipe 21 which in turn is connected through the union 22 with an ejector C by means of which a stream of oil is induced and delivered to the inner tube 12 in a manner to be 70 made clear hereafter.

The ejector C is provided with a conduit 23 the bore of which tapers from intermediate of its length outwardly towards 75 both ends and in the shorter tapered end a steam nozzle 24 is located.

This steam nozzle is positioned by a coupling 25 and is adapted to be connected by the pipe 26 to the pipe 27 which is attached 80 through a pipe line to the dome 28 of the boiler so that dry steam will flow through the pipe 27 into the conduit 26 and thence through the nozzle 24 and conduit 23 and be delivered into the inner tube 12. 85

This flow of steam can be regulated by the manually operated valve 29 to suit the requirements and the well-working of the device. The ejector C is provided intermediate of its length with an inlet opening 30 which is connected to the pipe 31 communicating with the oil reservoir 32 and the pipe 31 is provided with a valve 33 by means of which the flow of oil delivered to the ejector C may be manually controlled. 90 95

In the embodiment illustrated the pipe 20 is shown connected to the pipe 27 by means of a T-piece but it will be understood that super-heated steam from any source might be delivered through the pipe 20 to the 100 chamber 19 and the object in showing the connection illustrated in Figure 1 was for simplicity of connection and to dispense with a plurality of steam pipes.

When a boiler is fitted with a burner of 105 this description, and after steam has been

initially raised, the valve 29 is regulated allowing steam to flow from the dome 28 through the pipe 27 to the nozzle 24 and the valve 33 is then opened to allow oil 5 to flow from the reservoir 32 into the pipe 31 and be thus delivered to the ejector.

As the steam passes from the nozzle 24 through the conduit 23 an entraining action takes place and a film of oil passes into the 10 conduit 23 where intermixing with the steam it is partially vaporized and passing through the pipe 21 into the tube 12 is discharged through the slots 13 in thin films.

15 Superheated or dry steam simultaneously passes from the pipe 20 into the chamber 19 and there meeting with the partially atomized oil and steam completes the atomization and the combustible mixture is discharged from the curvilinear slots 18 in the 20 cap 17 where it is lighted.

When the boiler is in full working order the valves 29 and 33 may be adjusted to give the desired amount of combustion to 25 maintain the steam in the boiler A at the desired predetermined pressure.

It will thus be seen that the operation of the burner is manually controlled to give the best possible efficiency while the arrangement of the several parts is such that 30 they may be readily inspected at all times.

It should also be carefully borne in mind that there are no moving parts in the burner and this consequently reduces the liability of the burner going out of working 35 order.

In some heating systems hot water is used in low pressure boilers and consequently the oil could not be vaporized from

the boiler itself as above described by using 40 steam, but in such circumstances the pipe line to which the pipe 27 is connected is not attached to the dome of the boiler but is connected to a supply of compressed air which is designed to perform the functions 45 of the steam. The construction of the burner however remains the same and it is therefore deemed unnecessary to redescribe the burner in combination with a compressed air reservoir.

As many changes could be made in the above construction and many apparently widely different embodiments of my invention within the scope of the claims, constructed without departing from the spirit 55 or scope thereof, it is intended that all matter contained in the accompanying specification and drawings shall be interpreted as illustrative and not in a limited sense.

What I claim as my invention is:

An oil burner of the class described comprising a tube provided with a plurality of curvilinear slots therein, a pipe surrounding the tube and spaced therefrom forming an annular passageway, a jet on the pipe having curvilinear slots therein, ejector means for delivering a mixture of oil and fluid to the tube and means for delivering fluid to the annular chamber to inter-mix 65 with the fluid and oil and complete the vaporization of the oil.

In witness whereof I have hereunto set my hand in the presence of two witnesses.

EDWIN JAMES GARFIELD MacINTYRE.
